CLAIM

The ornamental design for a top for a lavatory, as shown and described.

DESCRIPTION

FIG. 1 is a top right perspective view of a top for a lavatory showing our new design;

FIG. 2 is a top plan view thereof;

FIG. 3 is a cross sectional view taken along line 3—3 of FIG. 2; and,

FIG. 4 is a cross sectional view taken along line 4—4 of FIG. 2.

The broken line representation of a lavatory basin in FIGS. 3 and 4, and of a countertop in FIG. 1, are for illustration only and form no part of the claimed design.

FIG. 3

FIG. 4
